UNITED STATES PATENT OFFICE.

GEORGE H. DAWSON, OF CAMBRIDGE, MASSACHUSETTS, ASSIGNOR TO LIBRARY BUREAU, A CORPORATION OF NEW JERSEY.

INDICATING SYSTEM AND SIGNALS FOR CARD INDEXES.

Application filed December 5, 1921. Serial No. 520,188.

To all whom it may concern:

Be it known that I, GEORGE H. DAWSON, a citizen of the United States, and a resident of the city of Cambridge, in the county of 5 Middlesex and State of Massachusetts, have invented certain new and useful Improvements in Indicating Systems and Signals for Card Indexes; and I do hereby declare that the following is a full, clear, and exact 10 description of the same, reference being had to the accompanying drawings, and to the numerals of reference marked thereon, which form a part of this specification.

This invention relates to visible card index 15 systems in which a series of cards are mounted in a tray or the like in overlapping relation with their lower edges exposed.

It is an object of this invention to provide a system of indicators in combination with 20 the cards whereby conditions of accounts or other special matter may be readily indicated.

My invention comprises the novel structure arrangements and combinations herein- 25 after described and more particularly pointed out and defined in the appended claim.

In the accompanying drawings which illustrate a preferred embodiment of my invention and in which similar reference 30 numerals refer to similar features in the different views:

Figure 1 is a fragmentary front elevational view of a tray supporting a system of index cards involving my invention.

Figure 2 is a front elevational view of 35 a mounted card removed from the tray, on an enlarged scale.

Figure 3 is a broken edge view of the 40 mounted card shown in Figure 2, upon an enlarged scale.

Figure 4 is an edge view of the transparent protective sheet that covers the front face of the card, upon an enlarged scale with reference to Fig. 1.

45 Figures 5, 6 and 7 illustrate differently colored indicators forming part of this invention.

As shown on the drawings:

For the purpose of illustrating my invention, I have shown a card tray or frame 1 having guide channels in its lateral edges for receiving the ends of the card-supporting bars 2 to which the flexible hinge members 3 are secured which in turn removably 55 support the index cards 4. For this pur-

pose, the flexible hinge members are provided with studs 5 to which inwardly turned flaps 6 on the hinge members are secured, and the cards are provided with elongated notches at their upper lateral edges which are designed to receive said studs under the flaps 6. The cards are mounted and removed from the studs by flexing the same between the notches as is 60 obvious.

Each card is protected on its front face by means of a transparent sheet 7 having a lower upwardly turned flange 8 designed to rest against the rear surface of the card when the same is mounted. The upper 70 lateral edges of each transparent sheet are provided with notches adapted to align with the notches in the card so that the transparent sheet may be superposed on the front face of the card with the card between the flange 8 and the main portion thereof and be mounted simultaneously with the card on the same support.

The exposed edge of each card is adapted to have the name of a customer, client, or 80 any person or firm written thereon, as indicating his or their account or data, and as it is frequently desirable to tell at a glance the nature of the account or data, standing of the person, or amount due, or for any 85 other purpose, differently colored indicators 9, 19 and 11 are used for the different cards; each different color having a certain significance.

These indicators comprise small tabs of any suitable material such as celluloid having narrow lips 12 which engage around the bottom and rear of the cards inside the transparent sheet 7 as shown in Figure 3. They are usually applied before the sheet 7 is superposed on the card and 90 may be adjusted to any longitudinal position thereon, for indicating further information. And for the purpose of designating this information, an index element 12 is 95 preferably mounted in the tray above the uppermost card and marked with the information designating the different adjustments. For the purpose of illustration, said index element 12 is shown as giving information relative to three different adjustments of the indicators, the first position of an indicator constituting first notice, the second position constituting second notice, and the third position constituting third notice. It is, however, contemplated that 100

the different adjustments of the indicators may be used to convey or indicate any different or desired information.

It is further desirable at times to call 5 particular attention to one or more cards from a number having similar indicators or to specially designate certain ones of a group and for this purpose I have shown apertures 13 in certain indicators at random, 10 and these apertures may serve as symbols for calling particular attention to those cards or designating them from others of the same class.

These indicators are always in plain view, 15 so an observer can tell at a glance the condition of affairs relative to the person, firm or data recorded on the different index cards, and the task of examining the different cards is reduced to a minimum and 20 much time and labor is saved thereby.

I am aware that numerous details of con-

struction may be varied through a wide range without departing from the principles of this invention, and I therefore do not purpose limiting the patent granted thereon, 25 otherwise than necessitated by the prior art.

I claim as my invention:

In a card index system, a support comprising a hinge member, a card removably attached to said hinge member, an indicator 30 having a lip engaging over the lower edge of said card, and a transparent sheet having a lower lip engaging over said indicator and removably attached to said hinge member.

In testimony whereof I have hereunto 35 subscribed my name in the presence of two subscribing witnesses.

GEORGE H. DAWSON.
